UNITED STATES PATENT OFFICE

132,344

DESIGN FOR A DISH OR SIMILAR ARTICLE

George E. Gregory, Providence, R. I., assignor to
Oneida Ltd., Oneida, N. Y., a corporation of
New York

Application August 29, 1941, Serial No. 103,080

Term of patent 7 years

To all whom it may concern:

Be it known that I, George E. Gregory, a citizen of the United States, residing at Providence, county of Providence, and State of Rhode Island, have invented a new, original, and ornamental Design for a Dish or Similar Article, of which the following is a specification, reference being had to the accompanying drawing, forming a part thereof, in which the figure is a plan view of a dish or similar article, showing my new design, a repeat unit of which is contained be-

tween the dotted lines. Said unit is understood to be repeated in regular succession around the plate and as indicated beyond the unit boundaries.

The dominant features of the design reside in the ornamentation shown in full lines in the drawing.

I claim:

The ornamental design for a dish or similar article, substantially as shown and described.

GEORGE E. GREGORY.
